UNITED STATES PATENT OFFICE.

JOHN A. BAILEY AND CLAUDE F. PURKITT, OF WILLOWS, CALIFORNIA.

TIRE-PROTECTOR.

967,704.

Specification of Letters Patent. Patented Aug. 16, 1910.

Application filed May 22, 1909. Serial No. 497,824.

To all whom it may concern:

Be it known that we, JOHN A. BAILEY and CLAUDE F. PURKITT, both citizens of the United States, residing at Willows, in the county of Glenn, State of California, have invented a new and useful Tire-Protector, of which the following is a specification.

The present invention resides in a protector for pneumatic tires, and especially, for the inner tubes thereof; the object being the production of a protector, which will possess great elasticity.

Another object of this invention is the production of a tire protector, which is made up of a plurality of links or sections, which may be readily detached from each other.

Other objects of this invention will also appear in the following specification and claim.

20 In the drawings Figure 1 is a perspective view of the protector. Fig. 2 is a perspective view of one of the links or sections, looking at the inner side of the same. Fig. 3 is a perspective view of one of the links or sections looking at the outer side of the same. Fig. 4 is a view of a number of sections or links, shown connected together, looking at the outer surface thereof. Fig. 5 is a view of the same looking at the inner surface thereof. Fig. 6 is a perspective view of the expandible link, showing the sections drawn apart.

Referring to the drawings by numerals 1 designates the protector which comprises a plurality of links or sections 2; each link being provided with a concave inner surface and a convex outer surface. Each of the sections 2 is provided with a tongue 3 upon one end, which is folded upon the body portion 4, and which constitutes a hook as clearly shown in Fig. 2. Each section or link 2 is also provided with an elongated aperture 5 near the opposite end of the body portion 4, which extends transversely of the section or link. As stated before the protector is made up of a plurality of sections and the sections or links are adapted to overlap as shown clearly in Fig. 1; the tongue of one section fitting into the slot in the adjacent section and so on until a continuous band of links or sections is formed.

In Fig. 6 is shown another embodiment of a link which may be used in connection with the present invention, which link comprises a primary portion 6 and an auxiliary portion 7. The primary portion 6 is provided with a folded tongue or hook 8 similar to the hook 3 of the link 2 and is also provided with folded sides 9 as shown clearly in Fig. 6. The auxiliary member or portion 7 is provided with an elongated slot 10, and said auxiliary portion is adapted to slide upon the primary member or portion; the folded portion or sides 9, acting as guideways or tracks to prevent the lateral displacement 65 of the auxiliary portion of the primary portion.

It will be obvious that the primary and auxiliary portions constitute an expandible link thereby adding greatly to the elasticity 70 of the protector. It will be further obvious that by having a protector formed in accordance with the present invention, that if any of the sections should become broken or distorted, the same could be replaced by new 75 links, and also that the protector could be made to fit any size tire.

What we claim is:—

A detachable metallic inner tube protector for pneumatic tires comprising a plurality 80 of links, each link provided with a hook at one end and a slot near the other end, said links overlapping each other when coupled together, and a plurality of sections constituting a coupling link, one section provided 85 with overturned edges, the other section slidably mounted upon said first mentioned section, said first-mentioned section provided with a tongue adapted to engage the adjacent link and said last-mentioned section provided with a slot adapted to be engaged by the tongue of the adjacent link for connecting the coupling link to the other links.

J. A. BAILEY.
C. F. PURKITT.
